UNITED STATES PATENT OFFICE.

ARTHUR J. ROWLAND, OF SHELBURNE FALLS, MASSACHUSETTS, ASSIGNOR TO LAMSON & GOODNOW MANUFACTURING COMPANY, OF SHELBURNE FALLS, MASSACHUSETTS, A CORPORATION OF MASSACHUSETTS.

DESIGN FOR A FORK.

50,284.

Specification for Design.

Patented Feb. 6, 1917.

Application filed June 7, 1916. Serial No. 102,346. Term of patent 7 years.

To all whom it may concern:

Be it known that I, ARTHUR J. ROWLAND, a citizen of the United States of America, residing in the city of Shelburne Falls, county of Franklin, and State of Massachusetts, have invented a new, original, and ornamental Design for Forks, of which the following is a specification, reference being had to the accompanying drawing, forming part thereof.

Figure 1 is a side elevational view; and Fig. 2 is an edge elevational view showing the design of my improved fork.

My present invention is confined to the

configuration of the article in which the tines of the fork are formed straight, that is to say, the axis of the tines and handle would lie in a plane located midway between the opposite sides of the tines, as clearly shown in the accompanying drawings, particularly in Fig. 2.

I claim:

The ornamental design for a fork, as shown.

ARTHUR J. ROWLAND.
